UNITED STATES PATENT OFFICE

148,348

DESIGN FOR A TEAKETTLE

Herbert E. Brannon, Dryden, Mich.

Application September 7, 1946, Serial No. 133,131

Term of patent 7 years

(Cl. D44—25)

To all whom it may concern:

Be it known that I, Herbert E. Brannon, a citizen of the United States, residing at Dryden, in the county of Lapeer and State of Michigan, have invented a new, original, and ornamental Design for a Teakettle, of which the following is a specification, reference being had to the accompanying drawing, forming a part thereof.

In the drawing:

Figure 1 is a top plan view of a teakettle embodying my design with a portion of the handle cut away in order to illustrate the appearance of the cover, the cut away portion of the handle being shown in dotted lines; and

Figure 2 is a side view of the teakettle shown in Figure 1.

I claim:

The ornamental design for a teakettle, substantially as shown and described.

HERBERT E. BRANNON.
